UNITED STATES PATENT OFFICE.

HENRY B. NICHOLS AND GEORGE M. RICHARDSON, OF PHILADELPHIA, PENNSYLVANIA.

BRAKE-SHOE.

1,111,606.

Specification of Letters Patent. Patented Sept. 22, 1914.

Application filed March 27, 1914. Serial No. 827,671.

To all whom it may concern:

Be it known that we, HENRY B. NICHOLS and GEORGE M. RICHARDSON, citizens of the United States, residing at Philadelphia, in the county of Philadelphia and State of Pennsylvania, have invented certain new and useful Improvements in Brake-Shoes, of which the following is a specification, reference being had therein to the accompanying drawing.

Our invention relates to railway equipment, automobiles, motor cars, wagons and other similar vehicles, and has for its object, the improvement of brake shoes in certain particulars which will be hereinafter set forth.

Heretofore, it has been common practice to make brake shoes of cast iron, which material in itself is subject to a number of objections. One of these is its granular tendency, and another its disposition to break across the middle, especially when partly worn through. On the other hand, steel shoes have been made of such a composition that the metal would have much greater intrinsic strength which would sufficiently resist the tendency to fracture, but ordinary steel, will not, under modern operating conditions, develop as high a coefficient of friction as some special mixtures of iron. In both iron and steel shoes, the braking quality or frictional resistance has been improved by the use of inserts, particularly such as are covered by United States Letters Patent to Stromeyer, Nos. 665,381, August 7, 1900, 866,085, September 17th, 1907, and 966,616, August 9th, 1910.

Cast iron, which is the cheapest material, all things considered, for this purpose, has heretofore been chilled in order to increase its life by retarding the wear, and it has been proposed to strengthen it by different forms of inserts of tougher and more ductile metal. It is the aim of our present invention to produce a composite shoe of this general type, which will be simple and

cheap to manufacture, and at the same time will afford maximum wear with minimum breakage.

We attain our object by providing a longitudinal strip of ductile or wrought iron or steel for the back of the shoe, combining therewith a separately formed lug of the same ductile or malleable iron or steel, and then casting the body so that the ductile parts will be partially embedded in the cast iron. In order to lengthen the life of the shoe, and at the same time give greater braking power, we provide the body with cells in which a suitable composition is placed, as is above mentioned.

As will hereinafter more fully appear, we introduce a number of detailed features of improvement, such as the use of spot welding to connect the malleable iron parts and the like.

Our invention is illustrated in the accompanying drawings in which—

Figure 1 is a perspective view of a brake shoe constructed in accordance with our invention. Fig. 2 is a similar perspective view of a form of stiffening strip or ductile back for the shoe. Fig. 3 is a perspective view of a ductile or malleable iron lug. Figs. 4, 5, 6 and 7 are all transverse sectional views of modified forms of lug showing different methods of securing the extremities of the lug to the backing strip. Fig. 8 is a perspective view of a modified form of lug adapted to afford side bearing surfaces of the malleable iron without the interposition of cast iron as in Fig. 1. Fig. 9 is a longitudinal sectional view of the shoe shown in perspective in Fig. 1. Fig. 10 is a face view of the shoe.

Referring to the drawings and particularly to Figs. 1, 2 and 3, 1 indicates a backing strip or reinforce for the brake shoe, this strip being made of ductile or malleable iron or mild steel. As shown in Fig. 2, it is preferably provided at its ends with circular openings 2, and intermediate its ends with

opposite recesses 3, intended to receive the ends of the lug 4. This lug 4 is made of the same malleable iron or mild steel as the strip 1, and is constructed in a peculiar way in order to secure maximum strength and resistance to distortion or breakage. It is composed of two members 4^a and 4^b, both of which are formed in substantially U-shape, inverted, with the member 4^b placed inside 5 of the member 4^a and their flat closed portions or bases permanently and integrally joined by means of spotwelding indicated by the circles at 4^c. This use of welding is a rather important feature of the present invention, as it entirely obviates a number of difficulties which have heretofore arisen wherever any member like this lug has been made in two parts secured together. Rivets work loose, and the junction produced by 10 embedding the two parts together in a casting is not always secure and is very far from being stiff enough for such purposes as ours. We find however that our duplex lug with the spotweld gives as good results in practice 15 as a solid lug and with no liability to fracture 20 25.

To complete the simplest form of shoe such as that shown in Fig. 1, we assemble the parts of Figs. 2 and 3 by placing the inverted U-shape member 4^b of the yoke in Fig. 3 astraddle of the strip 1, with the in-turned lower ends of the yoke member turning in under the edges of the recesses 3. It should be observed that this combination 30 can be made without the recesses, but in that case either the strip 1 must be much narrower, or the member 4^b must of course be much wider. We prefer the proportions shown in Figs. 1 to 3, and for this specific 35 arrangement provide the recesses. The parts 1 and 4 thus conjointly arranged are placed in the mold, and the body 5 of the shoe is cast in the form shown in Figs. 1, 9 and 10. In the matter of shape, the distinguishing characteristics of this form are 40 first the upstanding extensions 5^a and the end projections 6. The former are part of the cast iron, which in the pouring fills the spaces between the members 4^a and 4^b of 45 the yoke, and by reason of the formation of the pattern, extend beyond the opposite edges of the yoke members, sloping obliquely from the bases 5^b to the crowns 5^c, where they are flush with the edges of the yoke 50 member 4. In practice, this slope is not very sharp, the spread at the base being only $\frac{1}{2}$ inch, that is to say if the width of the yoke member 4 is $1\frac{1}{2}$ inches, then the width between the base lines 5^b would be $1\frac{1}{4}$ inches, 55 giving a projection of $\frac{1}{8}$ inch on each side. The purpose of this projection of the cast metal beyond the edges of the strap metal lug is to afford a better fit and a perfect bearing surface for the lug in the socket, 60

The principal strain of course comes entirely on these faces in braking, and while the lug 4 is strong enough, with its ends anchored in the casting as shown, to resist longitudinal displacement from the shoe, nevertheless its greatest strength is exerted 65 where it should be, that is around the key passed through its arch to lock it in the socket of the brake shoe holder. 70

The second characteristic feature, that of the projection 6, is due to a lug and flange 75 of cast metal at each end of the shoe, which in pouring flows through and covers one or the other of the openings 2. The primary purpose of this is to afford secure anchorage for the ends of the stiffening 80 strip. As a matter of fact, we believe, and our tests confirm the belief, that we have by this construction fully solved the problems stated in the preamble of this specification, and have fully attained our objects 85 therein referred to. Our shoe has a cast iron body which gives cheapness and braking efficiency, with an added efficiency by using the Stromeyer inserts. It has strength and decreased liability to fracture 90 due to the insertion of the malleable iron or steel stiffening strip 1; it has ideal support and bearing surfaces by reason of the material and construction of the bridge or yoke 4, and the extensions 5^a of the cast 95 body; and finally it has extreme rigidity and firmness in its assemblage by reason of the complete reinforced anchorage of all the malleable parts which are so embedded in the process of casting that the entire 100 structure becomes an integral and indivisible unit.

Referring to Figs. 4 to 8 inclusive, we have therein shown a number of modifications of the lug and of the method of securing the lug to the stiffening strip and the body of the shoe. In Figs. 4 and 5, the member 4^b is shown with shorter arms than the member 4^a, these arms being turned inward so as to lie over and upon the stiffening 105 strip 1, instead of being anchored beneath it. In order to present a smooth upper surface for the passage of the key, the stiffening strip is slightly recessed at 1^b (best shown in Fig. 5), and the ends of the member 4^b 110 are integrally secured thereto by means of spot welds 1^c. In assembling, the stiffening strip and lug thus become a unit, which is secured in the mold and anchored in the casting 115 the same as before. 120

In Fig. 6 we show another modification, in which the stiffening strip 1 still has the recesses 3 in its opposite sides, but the metal is turned down at 1^d along the inner edge of each recess, and the lower ends of the member 4^b, instead of being bent inward are carried down and spot welded to the metal flanges 1^d, as indicated at 1^e. This leaves a 125

smooth flush upper surface to the stiffening strip, and affords a very secure anchorage in the casting.

In Fig. 7 the construction is substantially the same as in Fig. 6, except that the lower ends of the member 4^b are welded directly to the edges of the stiffening strip 1, without any turned down flanges.

Fig. 8 shows in perspective, and with some exaggeration, a modified form of lug, having taper edges intended to take the place as bearing surfaces of the cast projections 5^a in Figs. 1 and 9. The inner and outer members on both sides of the lug 4 are split from base 15 to crown, and spread apart so as to be one-quarter inch wider at the base than at the crown. The ends of the member 4^b may be formed in any of the shapes shown in the other figures, the distinguishing feature of 20 this modification being the expanded taper of the ductile metal lug.

Having thus described our invention in terms of the best specific embodiments of which we are at present aware, we wish to 25 state and to have clearly understood, that we are aware these embodiments can be modified in diverse particulars without departing from the spirit of the invention. We contemplate all such modifications as 30 fall within the scope of the appended claims.

It is also to be clearly understood that we do not regard nor use the metal projections 5^a as a "reinforce," but only as a filler, and to furnish bearing surfaces in the holder.

We are aware that it has been heretofore proposed to use some form of malleable iron or steel lug which, being weak in itself, required a projection of the casting for reinforcing its grip and strengthening its holding of the key which retains the lug in the 40 brake head. Our lug, by reason of its peculiar construction is amply strong and stiff. The projections 5^a however furnish very good bearing surfaces, and serve very well 45 as fillers.

Having thus described our invention, what we claim and desire to secure by Letters Patent is:

1. A brake shoe comprising a cast body, 50 a back made of ductile metal having fastening devices connected therewith, said back and the fastening devices being embedded in the body of casting, and the fastening devices being separated transversely of the 55 body so as to leave spaces between them, and projections from the cast metal associated with said fastening devices filling said spaces and furnishing bearing faces to take the thrust due to braking.

2. A brake shoe comprising a cast body, 60 a back made of ductile metal having one or more fastening devices connected therewith, said back and the fastening devices being embedded in the body of casting and being

secured together independently of the casting by means of welded joints.

3. A brake shoe comprising a back made of ductile metal of substantially the full length of the shoe, with openings at its ends and opposite recesses in its middle portion, a fastening lug composed of two members, also of ductile metal, made in inverted U-shape with one member secured within the other by means of base welds, and an iron body cast upon and about said back and lug so as to embed the same in the casting with the openings in the back filled and covered by the cast iron, and the members of the lug straddling the recessed portion of the back.

4. A brake shoe comprising a cast metal body and a ductile or malleable metal lug for securing it in the brake head, said lug being made in inverted U-shape with inner and outer members welded together at their bases and with their ends separately embedded in the cast body.

5. A brake shoe comprising a cast metal body and a ductile or malleable metal lug for securing it in the brake head, said lug being formed of two members secured together to form a double arch with united crown, and with its terminal members embedded in the casting of the body.

6. A brake shoe comprising a back made of ductile metal, a fastening device in the form of a double arch, one arch within the other, and a body cast upon the back and the ends of the fastening device so as to embed the same within it.

7. A brake shoe comprising a back made of ductile metal, a key lug made of two flat straps bent in U-shape, one within the other, with the ends straddling the back and the inner ends anchored thereunder, and a body cast upon the back so as to embed the same and the ends of the lug within it.

8. A brake shoe having a malleable back with its ends anchored in the cast body, and a key lug formed of a double steel strap with one of its members within the other, both bent in U-shape, each with its ends anchored under the back of the shoe.

9. A brake shoe consisting of a back made of ductile metal, a fastening lug straddling the back and composed of an inner and an outer inverted U-shaped member, in combination with a cast metal body embedding the back and the ends of the lug members, with projections from the casting extending outwardly to fill the spaces between the inner and the outer members.

10. A brake shoe consisting of a back made of ductile metal, a fastening lug straddling the back and composed of an inner and an outer inverted U-shaped member, in combination with a cast metal body embedding the back and the ends of the lug

members, with projections from the casting extending outwardly to fill the spaces between the said members, and laterally to form bearing faces on opposite sides of the 5 lug.

11. A brake shoe comprising a back made of a ductile metal, an inverted U-shaped strap straddling said back and having its ends welded thereto, means for reinforcing 10 said strap, and a cast metal body embed-

ding the back and thereby being attached to the strap.

In testimony whereof we affix our signatures in presence of two witnesses.

HENRY B. NICHOLS.
